J. R. FRY

RELAY CONTROLLING SYSTEM

Filed Aug. 24, 1921

Inventor:
Jacob R. Fry.
by Websterly Atty

UNITED STATES PATENT OFFICE.

JACOB R. FRY, OF NEW YORK, N. Y., ASSIGNOR TO WESTERN ELECTRIC COMPANY,
INCORPORATED, OF NEW YORK, N. Y., A CORPORATION OF NEW YORK.

RELAY-CONTROLLING SYSTEM.

Application filed August 24, 1921. Serial No. 495,035.

To all whom it may concern:

Be it known that I, JACOB R. FRY, a citizen of the United States, residing at New York, in the county of Bronx, State of New York, have invented certain new and useful Improvements in Relay-Controlling Systems, of which the following is a full, clear, concise, and exact description.

This invention relates to circuit arrangements, and more particularly to circuit arrangements for controlling the operation of relays.

It is the object of this invention to provide a circuit arrangement such that a relay may be operated in response to the application of fluctuating or intermittent current of certain characteristics, and will not respond to fluctuating or intermittent current of other characteristics.

20 A feature of the invention is the use of induced currents for operating a relay. The coil by means of which currents are induced into the relay circuit is so designed that fluctuating current of certain characteristics applied to the primary winding of said coil will cause the relay to operate, while fluctuating currents of other characteristics will not cause the actuation of the relay.

It is believed that an arrangement of this 30 type has a wide field of utility, and the invention is therefore not to be limited by the specific disclosure, which merely shows the invention adapted to meet the requirements of a field in which it is particularly useful.

35 The invention has been shown in connection with a cord circuit arranged for the use of an operator at a private branch telephone exchange, in which some of the stations are arranged for through dialing. In a system

40 of this type it is desirable that a signaling device be provided which may be controlled by a relay which is responsive to ringing current applied at a distant exchange in case the operator thereat desires to recall the private branch exchange operator. In some

45 systems of this nature difficulties have been encountered in insuring the correct operation of a relay of this type and the signal controlled by it, due to the fact that when 50 the private branch exchange operator has established a through connection to an outgoing trunk by means of which a subscriber may dial to set up connections in the automatic exchange, it may occur that intermittent current flow caused by the interruptions

of the line circuit due to the manipulation of the subscriber's dial, will cause the energization of the signal controlling relay. By means of the controlling circuits provided in accordance with this invention, the signal 60 may be operated in response to the application of ringing current by an operator at the distant station, but will not be operated in response to any manipulation of a calling subscriber's dial.

65 It is thought the invention will best be understood from the following detailed description, reference being had to the accompanying drawing.

In the drawing is shown a private branch 70 exchange operator's cord circuit together with a station in the private branch exchange, and an outgoing trunk leading to automatic switches at a central office by means of which a connection may be extended to a called substation. The lower right-hand portion of the drawing shows part of an incoming trunk circuit, by means of which calls from outside offices may be extended to stations in the private branch 75 exchange.

The operation of the system when a subscriber in the private branch exchange desires a connection with another subscriber, whose station is in the same private branch 85 exchange, will first be described.

Assuming that substation 1 represents the station of the calling subscriber, the removal of the switchhook at such station causes the illumination of lamp 4, due to the completion of a circuit from battery, lamp 4, spring contact 3, the substation apparatus, spring contact 2, to ground. The illumination of lamp 4 attracts the attention of an operator, who answers the call by inserting 90 the answering plug 5 into the jack 6 of the calling station. The insertion of plug 5 into jack 6 opens the circuit of lamp 4, and this lamp is extinguished. A circuit is also completed from battery, lamp 9, 100 armature and back contact of relay 10, right armature and back contact of relay 11, sleeve contacts of plug 5 and jack 6, to ground. Calling supervisory lamp 9 is illuminated, but answering supervisory lamp 105 7 is not illuminated at this time since answering supervisory relay 8 is operated. The operating circuit for relay 8 may be traced from battery, the outer left armature and back contact of relay 11, lower 110

winding of induction coil 20, winding of relay 8, lower normal contact of key 29, ring contacts of plug 5 and jack 6, the line loop and the apparatus at substation 1, tip 5 contacts of jack 6 and plug 5, upper normal contact of key 29, upper winding of induction coil 20, and inner left armature and contact of relay 11, to ground. The operator depresses listening key 34 to connect her telephone head set across the tip and ring conductors of the line, and converses with the calling subscriber. Upon learning that the call is for a station in the private branch exchange, she inserts plug 16 10 into another jack corresponding to jack 6, but serving the called subscriber, and depresses ringing key 30 to signal the called subscriber in the usual manner.

In order to keep the description and disclosure as simple as possible, it will be assumed that the stations in the private branch exchange are represented at the operator's position by one jack only which serves both as the calling and answering 20 jack. When the operator plugs into a jack 6, the control of lamp 4 is removed from the subscriber to whom such jack is assigned, regardless of whether the operator plugs in to answer a call or to signal a wanted station. The insertion of plug 5 causes spring contacts 2 and 3 to be opened to prevent further illumination of the lamp.

The operator intermittently actuates ringing key 30 until the called subscriber responds. The response of the called subscriber is indicated to the operator by the extinguishment of lamp 9 due to the energization of calling supervisory relay 10. Relay 10 is energized in a circuit from battery, outer left armature and back contact of relay 11, lower winding of induction coil 20, winding of relay 10, lower normal contact of relay 15, lower normal contact of key 30, ring contacts of plug 16, the jack corresponding to jack 6, and through the loop of the called substation line, tip contacts of plug 16 and associated jack, upper normal contact of key 30, upper normal contact of relay 15, upper winding of induction coil 20, inner left armature and back contact of relay 11, to ground.

Talking current is supplied to the called subscriber over the circuit above traced. Talking current is supplied to the calling subscriber from the same source through answering supervisory relay 8 and the tip and ring conductors of the cord circuit in an obvious manner.

When conversation is completed and connection is no longer desired, the calling and called subscribers replace their receivers, thus causing the deenergization of supervisory relays 8 and 10 respectively, and the illumination of supervisory lamps 7 and 9. Upon observing the lighting of lamps 7 and 9 the

operator removes plugs 5 and 16 from the jacks with which they have been associated, thus restoring the control of the line signals to the respective subscriber.

The operation of the system in case a subscriber in the private branch exchange desires a connection to a subscriber in a distant mechanical office will now be described.

The call is originated and answered and conversation takes place between the calling subscriber and the operator in the same manner as previously described and lamp 9 is illuminated as previously described.

The operator now proceeds to test in the well known manner trunk jacks correspond-

80

ing to jack 17 until an idle trunk is encountered whereupon plug 16 is fully inserted into the jack of such idle trunk.

85

A circuit is then completed from battery, winding of relay 18, sleeve contacts of jack 17 and plug 16, winding of relay 11, to ground.

90

Relay 11 is energized in this circuit and at its right armature opens the circuit of lamp 9 which is thereupon extinguished. The energization of relay 11 also completes a

95

circuit from battery, outer left armature and front contact of relay 11, winding of relay 13, armature and front contact of relay 8, sleeve contacts of plug 5 and jack 6, to ground, for causing the energization of re-

95

lay 13, which locks through its left armature to ground at a normal contact of the operator's listening key 34. It should be observed that the energization of relays 11

100

and 13 disconnects the source of battery supply from the primary windings of induction coil 20, and bridges these windings across the tip and ring conductors of the cord circuit with condenser 12 in series there-

105

with. Relays 8 and 10 remain energized by means of current supplied over the trunk conductors and lamps 7 and 9 are maintained extinguished.

The operator now proceeds to direct automatic switches, brushes of which are indicated generally at 22 and 23, by means of a calling dial 21 of any well known type.

110

As soon as the dial leaves its normal position, contact 40 is closed and a circuit is completed from grounded battery, contact 40,

115

winding of relay 15, to ground. Relay 15 is energized and extends the tip and ring trunk conductors through to the impulse

120

spring contact 41 which is intermittently operated during the return movement of the dial. After the operator has dialed all of the digits of the wanted number, contact 40

125

is opened and relay 15 releases so that she is free to answer another call. The called station, indicated in this case at 24, is signa-

130

led in the well known manner by means of ringing apparatus associated with the automatic switches. The calling and called subscribers are supplied with talking current from one of the automatic switches in the

well known manner and current flow through the tip and ring conductors and the connecting circuits maintains relay 8 energized to prevent the illumination of lamp 7. Lamp 9 is not illuminated at this time due to the fact that relay 11 is energized over this lead circuit.

When the conversation is completed, the subscribers replace their receivers and cause the release of the automatic switches in the well understood manner. The release of the automatic switches disconnects the source of current supply from the trunk, thus allowing relays 8 and 10 to be released, causing in turn the illumination of lamp 7. The operator upon observing the lighting of this lamp removes plugs 5 and 16 from jacks 6 and 17 respectively. Relay 11 is thereupon released and causes the deenergization of relay 13 leaving the apparatus in its normal condition.

In case a call is to be extended from a distant office to a station in the private branch exchange, the operation is as follows. The trunk associated with jack 25 shown in the lower right-hand portion of the drawing is seized at the distant point either by an operator or by an automatic switch. Closure of the trunk line loop causes the energization of relay 27 and the resultant illumination of trunk signal lamp 28. The private branch exchange operator upon observing the lighting of signal lamp 28, inserts plug 16 into trunk jack 25 whereupon a circuit is completed from battery, winding of cut-off relay 26, sleeve contacts of jack 25 and plug 16, and the winding of relay 11, to ground. Relays 11 and 26 are energized in this circuit, relay 11 opening the circuit of lamp 9 and preventing its operation, while relay 26 causes the release of relay 27 and the resultant extinguishment of lamp 28. By depressing listening key 34 the operator may converse with the distant operator or the subscriber initiating the call and learn the number of the line wanted in the private branch exchange. She thereupon inserts plug 5 into the jack 6 and signals the wanted station by means of ringing key 59 which is actuated intermittently until the called subscriber answers, whereupon the energization of relay 8 causes lamp 7 to be extinguished. Lamp 7 was lighted as soon as plug 5 was inserted into jack 6. With relays 8 and 11 energized, the previously traced circuit for relay 13 is again completed and this relay is energized and locked as previously described. Supervision is accomplished as previously described and the illumination of lamps 7 and 9 gives the operator the disconnect signals. The removal of plugs 5 and 16 from their associated jacks causes the restoration of the apparatus in an obvious manner.

It should be noted that if the operator at

the distant exchange wishes to recall the private branch exchange operator for any reason, she may do so simply by applying ringing current across the tip and ring conductors of the interoffice trunk. Ringing current flows in this circuit from a source of ringing current 44, upper contact of key 45, over the tip conductor of the trunk, tip contacts of jack 25 and plug 16, upper normal contact of key 30, upper normal contact of relay 15, upper primary winding of coil 20, inner left armature and front contact of relay 11, condenser 12, lower primary winding of induction coil 20, winding of relay 10, lower normal contacts of relay 15 and key 30, ring contacts of plug 16 and jack 25, and the tip conductor of said trunk, back to the source of ringing current 44 by way of the lower contact of key 45. Induction coil 20 is so designed that the application of ringing current to its primary winding allows sufficient current to be induced into its secondary winding to cause the energization of relay 19. The energization of relay 19 completes an obvious circuit for illuminating lamp 9 to give the private branch exchange operator the recall signal. The primary windings of induction coil 20 are designed to be of relatively high impedance, but the choking effect of this impedance is not sufficient to prevent passage of the substantially sinuous waves of ringing current in sufficient strength to cause energizing current for relay 19 to flow in the secondary winding of the coil.

In systems of the type under consideration it is frequently desirable that a through dialing connection be established by means of the operator's cord circuit from a station in a private branch exchange to a trunk leading to automatic switches. This may be desirable for several reasons. For instance, at night when the operator has left the board, it may be desirable to provide service to certain ones of the stations. Again, it may happen that a subscriber wishes to set up a number of connections in a distant automatic exchange, in which case it would be undesirable to have the operator give him a new trunk each time.

In the case of a through dialing connection the operator answers the call as previously described and then hunts for an idle trunk leading to the automatic exchange and inserts plug 16 into the jack 17 of such trunk. Relays 11 and 13 are operated as previously described as are also relays 8 and 10. The operator is then free to attend to other calls since the subscriber by manipulating his dial 42 may set up his own connections and release them at will as he has a full metallic two-conductor circuit from his substation to the switches which he can control in a manner well known in the art. The primary windings of induction coil 20

and condenser 12 in series therewith, are bridged across the line, but the interruptions of the line circuit due to the operation of dial 42 do not cause relay 19 to be energized to give a false recall signal to the private branch exchange operator. This is due to the fact that the high impedance of the primary windings of the coil 20 has a strong choking effect due to the fact that 10 the current fluctuations or changes are much sharper and occur at a different frequency than those of the ringing current.

It is further to be observed that the inclusion of relay 19, which controls the recall signal, in the secondary winding of an induction coil, the primary of which allows fluctuating current of certain characteristics to pass and prevents fluctuating currents of other characteristics to pass in appreciable 20 quantities, accomplishes a result which is highly desirable. That is, a control of relay 19 is accomplished by means of which this relay may be positively actuated by ringing current and be just as positively 25 prevented from operation due to fluctuations in the line during operation of the dial 42.

What is claimed is:

1. In a telephone exchange system, incoming and outgoing lines, a link circuit including talking conductors for interconnecting said lines, a signal associated with said link circuit, a relay to control said signal, an induction coil including a primary and a secondary winding, a circuit including 30 said relay and said secondary winding, a source of alternating current, means to apply said alternating current to the talking conductors of said link circuit, a source of potential, means to establish connection 35 from said source of potential to the talking conductors of said link circuit through the primary winding of said induction coil at one stage of operation, and means operative 40 at another stage of operation to bridge said primary winding across said talking conductors to induce operating current for said relay in said secondary winding when said alternating current is applied to display 45 said signal.
2. In a telephone exchange system, an incoming line, a plurality of variously characterized outgoing lines, a link circuit including talking conductors for extending 50

said incoming line to a desired one of said outgoing lines, a signal associated with said link circuit, a relay to control said signal, an induction coil including a primary and a secondary winding, a circuit including 55 said relay and said secondary winding, a source of potential, means operative when a connection is extended to an outgoing line of certain characteristics to supply current from said source to the talking conductors of said link circuit through the primary windings of said coil, and means operative 60 65 when a connection is extended to an outgoing line of other characteristics to bridge said primary windings of said induction coil across the talking conductors of said link circuit to render said relay responsive 70 to the application of alternating current to the talking conductors of said link circuit.

3. In a telephone exchange system, an incoming line, a plurality of variously characterized outgoing lines, a link circuit for extending said incoming line to a desired one of said outgoing lines, a signal associated with said link circuit, a relay to control said signal, an induction coil including a primary and a secondary winding, a circuit including 75 said relay and said secondary winding, a source of potential, means to utilize said primary winding either as a battery feed coil or as the primary winding of a transformer to operate said relay, in accordance 80 with the character of the outgoing line to which connection has been established.

4. In a telephone exchange system, an incoming line, a plurality of outgoing lines, a link circuit for extending said incoming line to a desired one of said outgoing lines, means for applying currents of different characteristics to the conductors of said link circuit, a signal associated with said link circuit, a relay for operating said signal, an induction coil including a primary and a secondary winding, a circuit including said relay and said secondary winding, said induction coil being arranged to permit the operation of said relay only in response to 95 100 the application of current of certain characteristics.

In witness whereof, I hereunto subscribe my name this 10th day of August A. D., 1921.

JACOB R. FRY.
